UNITED STATES PATENT OFFICE

158,775

DISPLAY STAND

Simon Malkin, New York, N. Y., assignor to Johnson & Johnson, a corporation of New Jersey

Application April 13, 1949, Serial No. 1,944

Term of patent 14 years

(Cl. D80—9)

To all whom it may concern:

Be it known that I, Simon Malkin, a citizen of the United States, residing at 60 Gramercy Park, city of New York, county of New York, and State of New York, have invented a new, original, and ornamental Design for a Display Stand, of which the following is a specification, reference being had to the accompanying drawing, forming a part thereof, wherein:

Fig. 1 is a front perspective view of a display stand showing my new design.

Fig. 2 is a side elevational view; and

Fig. 3 is a rear elevational view thereof.

I claim:

The ornamental design for a display stand, substantially as shown.

SIMON MALKIN.
